APPLICATOR FOR APPLYING COATING MATERIAL TO ROOFS AND SIMILAR SURFACES

Robert W. Turner, Port Jefferson, Ohio

Application August 31, 1948, Serial No. 47,025

12 Claims. (Cl. 91—25)

1

This invention relates to novel and useful improvements in apparatus for applying liquid material to surfaces such as in the formation of roofing and the like.

Another object of this invention is to utilize a chassis which is composed of a pair of sections hingedly mounted together with means for constantly urging the sections to a predetermined position with relation to each other, whereby the liquid application portions of the device may be 10 raised by flexing the chassis.

Another object of this invention is to pivotally mount a hopper carrier and hopper forwardly of the chassis, constantly vibrate the hopper carrier and hopper in a direction parallel to the 15 path of travel of the chassis, valve the hopper by manual means at the discretion of the operator of the device, and constantly reciprocate a brush forwardly of the egress portion of the hopper.

Another object of this invention is to conveniently locate the control for a heater which is attached to the hopper carrier, and the motor switch on a handle which is used for the purposes of propelling the device and also for opening and closing the valve.

Ancillary objects and features of novelty will become apparent to those skilled in the art, in following the description of the preferred form of the invention, illustrated in the accompanying drawings, wherein:

Figure 1 is a plan view of the preferred form of the invention;

Figure 2 is an elevational view of the invention shown in Figure 1, portions being broken away in section to illustrate details of construction, this view taken substantially on the line 2—2 of Figure 1 and in the direction of the arrows;

Figure 3 is a front view of the device shown in Figure 1, portions being broken away in section to illustrate internal structure;

Figure 4 is a fragmentary enlarged elevational side view of the device, portions shown in section for illustrative purposes of details;

Figure 5 is a sectional detail of construction showing particularly the means for reciprocating the brush at the forward end of the device;

Figure 6 is a sectional view taken substantially on the line 6—6 of Figure 2 and in the direction of the arrows;

Figure 7 is a fragmentary perspective view showing the valve actuation means and valve return means for the hopper; and

Figure 8 is an enlarged fragmentary detail

2

illustrating a portion of the vibration producing apparatus for the hopper carrier and hopper.

The present invention has been developed to incorporate various structural features of advantage over devices known in the art. By the utility of the structural features referred to the application of asphalt and other substances on floors, roofs, etc., become relatively easy. It is one of the prime purposes of the invention to render the workmen's task lighter and to perform a better application of a coat of such material on a surface.

The instant surface conditioner applies an even coat of material to the surface to be treated, after it has been acted upon by the brush mounted rearwardly of the vehicle. The amount of actual conditioner spread on the surface is selectively regulated by the operator of the device by mere manipulation of the same handle which he utilizes to propel the device.

Other structural and operational advantages will become apparent in viewing the drawings. Noting Figure 2 it will be seen that a chassis is illustrated which includes two sections 10 and 12 respectively connected together by means of a hinge generally indicated at 14. This hinge has two sections 16 and 18 in the makeup thereof with a spring 20 reacting on each hinge section and ultimately on the sections 10 and 12 of the chassis.

It is seen that the hinge is so constructed as to allow bending or flexing of the entire chassis to raise and lower the forward end having the wheel 22 mounted thereon and the rear end having the wheels 26 and 28 respectively carried thereby.

A support which includes a front plate 30 and a rear plate 32 is attached to the section 10 by any suitable conventional means and carries a shaft 34 at the upper ends of said plates. This shaft has a handle 36 rigidly secured thereto whereupon rotation of the handle produces corresponding rotation of the shaft 34. The function of the handle is threefold. It is used as a support for a heater control switch or rheostat-switch 38, a motor switch 40; it is used as an operating means for propulsion of the vehicle; and it is used for the purpose of imparting rotation to the sheave 42, alternately controlling the actuation of a valve mechanism.

A bracket type support 44 which is substantially U-shaped is attached at the web thereof to the plate 32 projecting rearwardly of the device. This support maintains a hopper carrier 55 having side walls, a rear wall 48 and a front wall

46. The supporting takes place through the utility of horizontal pivot pins 50 whereby the hopper carrier and hopper 52 mounted therein are mounted for pivotal movement about the pivot pins 50 as an axis so that the hopper bottom swings in a direction generally the same as the travel of the vehicle chassis.

Means for oscillating the carrier in very short strokes so that vibratory movement occurs is provided. The preferable means consists of a motor 54 which is mounted on the section 10 of the chassis and which has a drive shaft 56 depending therefrom and through the said section 10. This shaft has a pulley 58 attached thereto with a belt 60 entrained therearound. This belt also extends around a second pulley 62 which is mounted on a pin 64. The said pin (see Figure 8) is journaled in a bearing 66, which is in turn secured to the said section 10 by suitable means such as the screws 70 illustrated.

An eccentrically mounted pin 72 is attached to the pulley 62 to impart reciprocating movement to the pitman 74. A second pitman 76 is attached to the first mentioned pitman 74 through the medium of a universal joint 78 or other equivalent suitable flexible connection. The opposite end of the pitman 76 is joined to a flange 80 of the wall 46 of the hopper carrier through a pivotal connection seen at 82. It is apparent that torque from the motor 54 is imparted to the hopper carrier to vibrate the same. In order to control the actuation of the motor, the switch 40 is utilized. The conductor 84 connects with any suitable conventional electrical current outlet to energize the motor however, the switch 40 is interposed in that line to serve its intended function.

The material generally utilized for surface treating of the nature dealt with generally requires the application of heat to render it sufficiently fluid for flow. Accordingly, a heating element 86 is supplied in a housing 88. The said housing 88 extends around the hopper carrier in order to heat the contents of the hopper by conduction. An electrical conductor 90 extends appropriately from the heating element and terminates in the rheostat-switch 38 for control thereof.

A brush 92 which includes a brush holder 94 and bristles is attached rearwardly of the device for reciprocating movement in order to spread the substance after it has been emitted from the egress portion of the hopper. Brackets 96 and 98 respectively which are attached to the back wall 48 of the hopper carrier are used as hangers for the bifurcated pitman rods 100. One pair of ends of the pitman rods 100 is pivotally attached to the hangers 96 and 98 through the medium of any type of conventional pivot pin, while the other ends of the pitman 100 are pivotally connected to the brush holder element 94. This structure pivotally mounts the brush 92 for pivotal movement on the hopper carrier.

Means for imparting reciprocating movement to the brush is supplied. A preferred means includes a gear box 102 having the shaft 56 terminating therein, carrying a pinion. A shaft 104 is supported by a hanger 104 (see Figure 6), which is in turn mounted on the under surface of the section 10. At one terminal of the said shaft 104 there is a worm type gear 106, see Figure 5, rigidly attached which is enmeshed with the pinion on the terminal of the shaft 56. Accordingly, torque from the motor 54 is imparted through the structure within the gear box to cause rotation

of the shaft 104. An eccentric generally indicated at 107 is supplied at the opposite end of the shaft 104 for imparting reciprocating movement to the push rod 108. At the end of the push rod a bell crank 110 is pivotally connected therewith, the crank being pivotally journaled on the rear wall 48 of the said hopper carrier. Secured to an arm 112 of the said crank by means of a pin and slot connection 114 is an operating bar 116 which converts the arcuate movement of the crank to rectilinear reciprocation of the brush 92. Since the brush reciprocation mechanism is motor actuated, it will be operative while the hopper vibrating means is operative.

Disposed at the egress portion of the hopper is a valve including a valve plate 118 and a keeper 120 depending therefrom. The valve plate 118 is pivotally attached to the side walls of the hopper through the medium of conventional pivot means 122.

A crank 124 having at least two throws 126 and 128 respectively is mounted for rotational movement with the valve plate 118 through the medium of the eyes 130 and 132 respectively. The said eyes are located in the throws 126 and 128 in order that rotation of the crank 124 will impart pivotal movement to the valve plate 118.

One end of the crank seen at 134 extends substantially perpendicular to the longitudinal axis of the crank and has a cable 136 attached thereto. This cable is guided by means of a pulley 138 mounted on the U-shaped support bracket 44 and a second small pulley 140 mounted on the web of the said bracket 44. The cable 136 terminates on the sheave 42 in order that it may be wound thereon upon rotative movement of the handle 36 as described herein before.

It is quite apparent that rotation of the handle will cause pivotal movement of the valve plate 118 in order to allow more or less substance to be emitted from the hopper.

A pair of arcuate keepers 142 are pivoted to the end walls of the hopper carrier and the terminal portions thereof contact the flange 120 of the valve plate 118. A spring 144 or other suitable, equivalent resilient urging means is attached to the sides of the hopper carrier and the arcuate keepers in order to constantly and resiliently urge the valve plate in the valve closing position. Accordingly, rotation of the handle 36 urges the valve plate 118 to the open position against the biasing force of the springs 144, the plate 118 being automatically closed by the potential energy thereof.

Figure 2 discloses that the hopper is simply rested within the hopper carrier. However, it is contemplated by the present invention to utilize a clamping or latch mechanism of conventional description in order to positively retain the hopper within the hopper carrier, if it is found desirable.

In operation the device is propelled by grasping the handle 36 and moving it on the surface to be coated. The motor 54 is rendered operative, which, through the medium of the belt 60, described pulleys and eccentric arrangement disposed beneath the chassis, causes the hopper carrier to oscillate about the pivot pins 50 as an axis. Vibratory movement in an oscillatory manner is thus produced for vibrating the contents of the hopper to cause uniformity of dispersal of the material from the hopper.

In order to open and close the valve at the bottom of the hopper, it is only necessary to re-

tate the handle 36 which is used for the purpose of motivating the device in its line of travel. By rotating the handle, through the intermediate structure of a pulley and the cable 136 together with the other described structure, the crank 124 is rotated with the valve plate 118, opening the discharge end of the hopper more or less, against the biasing force of the spring 144.

In instances wherein heat is necessary to maintain the material in the fluent state, the heater 86 is rendered operative; the heater being preferably of the electrically operative type.

For increased beneficial result in spreading the fluent material after it has been deposited in the surface, the brush at the rear of the hopper with respect to the line of travel of the vehicle chassis is reciprocated through the crank and arm structure seen best in Figure 5. This crank, arm and shafting is rendered operative by the motor 54.

To render the brush effectual or ineffectual and to remove the brush slightly from contact with the spread material on the surface to be treated, it is only necessary to press downwardly on the handle 36 thereby hingedly operating the sections 10 and 12 about the hinge pin of the hinge 14.

It is apparent that variations may be made without departing from the spirit of the invention.

Having described the invention, what is claimed as new is:

1. A mobile surfacing apparatus comprising a wheeled chassis including a pair of sections hingedly connected together for movement about a first horizontal axis, a hopper pivotally carried by said chassis for movement about a second horizontal axis, an outlet valve attached to the hopper, and means mounted on said chassis for vibrating said hopper about the second horizontal axis.

2. A mobile surfacing apparatus comprising a wheeled chassis including a pair of sections hingedly connected together for movement about a first horizontal axis, a hopper pivotally carried by said chassis for movement about a second horizontal axis, a valve attached to the hopper, means mounted on said chassis for oscillating said hopper about the second horizontal axis, a brush mounted rearwardly of said hopper and means actuated by said oscillating means for reciprocating said brush in a substantially horizontal plane.

3. A mobile surfacing apparatus comprising a wheeled chassis including a pair of sections hingedly connected together for movement about a first horizontal axis, a hopper pivotally carried by said chassis for movement about a second horizontal axis, a valve attached to the hopper, means mounted on said chassis for vibrating said hopper about the second horizontal axis, a brush mounted rearwardly of said hopper and means actuated by said vibrating means for reciprocating said brush in a horizontal plane, and resilient means reacting on said sections for constantly urging said sections to a predetermined hinged position.

4. The combination of claim 3 and manually operative means secured to said chassis for actuating said valve, and a heater associated with said hopper for heating the contents thereof.

5. In a mobile surfacing device, a chassis, a hopper carrier pivotally mounted rearwardly of said chassis for movement about a substantially horizontal axis, means mounted on said chassis for vibrating said hopper carrier about said axis,

a hopper removably mounted in said carrier, an outlet valve secured to said hopper, resilient means reacting on said valve and said carrier maintaining said valve in the closed position, manually operative valve actuation means carried by said chassis, a brush and means mounting said brush for reciprocatory movement in a substantially horizontal plane rearwardly of said hopper carrier.

10. In a mobile surfacing device, a chassis, a hopper carrier pivotally mounted rearwardly of said chassis for movement about a substantially horizontal axis, means mounted on said chassis for vibrating said hopper carrier about said axis, a hopper removably mounted in said carrier, an outlet valve secured to said hopper, resilient means reacting on said valve and said carrier maintaining said valve in the closed position, manually operative valve actuation means carried by said chassis, a brush and means mounting said brush for reciprocatory movement in a substantially horizontal plane rearwardly of said hopper carrier.

15. A mobile surfacing device, a chassis, a hopper carrier pivotally mounted rearwardly of said chassis for movement about a substantially horizontal axis, means mounted on said chassis for vibrating said hopper carrier about said axis, a hopper removably mounted in said carrier, an outlet valve secured to said hopper, resilient means reacting on said valve and said carrier maintaining said valve in the closed position, manually operative valve actuation means carried by said chassis, a brush and means mounting said brush for reciprocatory movement in a substantially horizontal plane rearwardly of said hopper carrier, said carrier vibrating means including a motor, and means driven by said motor for reciprocating said brush.

20. The combination of claim 6 and a heater secured to said carrier for heating the contents of said hopper.

25. A surfacing device comprising a chassis including a pair of sections, a resiliently biased hinge having its axis horizontally disposed connecting said sections, wheels mounted on said sections, a motor carried by said chassis, a support disposed on said chassis, a handle pivotally mounted on said support, a hopper, a carrier for said hopper pivoted rearwardly of said chassis for movement about a substantially horizontal axis, a valve secured to said hopper, means actuated by said handle for actuating said valve, a brush mounted on said carrier for reciprocatory movement transversely of the pivotal movement of said carrier and in a horizontal plane, and means drivingly connected with said motor for reciprocating said brush.

30. A surfacing device comprising a chassis including a pair of sections, a resiliently biased hinge having its axis horizontally disposed connecting said sections, wheels mounted on said sections, a motor carried by said chassis, a support disposed on said chassis, a handle pivotally mounted on said support, a hopper, a carrier for said hopper pivoted rearwardly of said chassis for movement about a substantially horizontal axis, a valve secured to said hopper, means actuated by said handle for actuating said valve, a brush mounted on said carrier for reciprocatory movement transversely of the pivotal movement of said carrier and in a horizontal plane, and means drivingly connected with said motor for reciprocating said brush.

35. A surfacing device comprising a chassis including a pair of sections, a resiliently biased hinge having its axis horizontally disposed connecting said sections, wheels mounted on said sections, a motor carried by said chassis, a support disposed on said chassis, a handle pivotally mounted on said support, a hopper, a carrier for said hopper pivoted rearwardly of said chassis for movement about a substantially horizontal axis, a valve secured to said hopper, means actuated by said handle for actuating said valve, a brush mounted on said carrier for reciprocatory movement transversely of the pivotal movement of said carrier and in a horizontal plane, and means drivingly connected with said motor for reciprocating said brush, and means drivingly connected with said motor for pivotally vibrating said carrier.

40. A surfacing device comprising a chassis including a pair of sections, a resiliently biased hinge having its axis horizontally disposed connecting said sections, wheels mounted on said sections, a motor carried by said chassis, a support secured to said chassis, a handle pivotally mounted on said support, a hopper, a carrier for said hopper pivoted rearwardly of said chassis for movement about a horizontal axis, a valve secured to said hopper, means operatively connected with and actuated by said handle for actuating said valve, a brush mounted on said carrier for reciprocatory movement transversely of the

45. A surfacing device comprising a chassis including a pair of sections, a resiliently biased hinge having its axis horizontally disposed connecting said sections, wheels mounted on said sections, a motor carried by said chassis, a support secured to said chassis, a handle pivotally mounted on said support, a hopper, a carrier for said hopper pivoted rearwardly of said chassis for movement about a horizontal axis, a valve secured to said hopper, means operatively connected with and actuated by said handle for actuating said valve, a brush mounted on said carrier for reciprocatory movement transversely of the

pivotal movement of said carrier and, in a horizontal plane, means drivingly connected with said motor for reciprocating said brush, means drivingly connected with said motor for pivotally vibrating said carrier about the second mentioned horizontal axis, a heater attached to said carrier for heating the contents of said hopper, control means for said heater mounted on said handle, and at least one spring secured to said valve and said carrier for retaining said valve in the closed position.

11. A mobile servicing apparatus comprising a wheel chassis which includes a pair of sections, a hinge connecting said sections together and having its axis disposed in a horizontal plane, a hopper, means including horizontally disposed pivot pins pivotally securing said hopper to said chassis for pivotal movement about said horizontal pivot pins as an axis; means mounted on

said chassis for oscillating said hopper about said pivot pins as an axis, and a brush carried by said chassis.

12. A mobile servicing apparatus comprising a wheel chassis which includes a pair of sections, a hinge connecting said sections together and having its axis disposed in a horizontal plane, a hopper, means including horizontally disposed pivot pins pivotally securing said hopper to said chassis for pivotal movement about said horizontal pivot pins as an axis, means mounted on said chassis for oscillating said hopper about said pivot pins as an axis, and a brush carried by said chassis by a means operatively connected with

10. said oscillating means for reciprocating said brush in a substantially horizontal plane.
